WITNESSES

UNITED STATES PATENT OFFICE.

ALBERT L. WOODSIDE, OF BUTTE, MONTANA.

SUPPORT.

Application filed August 23, 1922. Serial No. 533,852.

To all whom it may concern:

Be it known that I, ALBERT L. WOODSIDE, a citizen of the United States, residing at Butte, in the county of Silver Bow and 5 State of Montana, have invented new and useful Improvements in Supports, of which the following is a specification.

The present invention has for its object, the provision of a device primarily designed 10 for use in conjunction with Buick automobiles and adapted to prevent vibration of the brake, radius of truss rods, which vibration causes crystallization, and resultant breakage.

15 Another object of the invention resides in the provision of a device for this purpose which can be manufactured and sold at a very nominal cost, and one which can be easily and conveniently arranged in position 20 upon the vehicle or removed therefrom as the occasion may require.

The nature and advantages of the invention will be better understood when the following detailed description is read in connection with the accompanying drawings, 25 the invention residing in the construction, combination, and arrangement of parts as claimed.

In the drawings forming part of this application, like numerals of reference indicate similar parts in the several views, and wherein:—

Figure 1 is a top plan view of the device showing it associated with the brake rods and with the radius or truss rods.

Figure 2 is a view in elevation of the device removed.

Figure 3 is a detailed view of the main section of the support.

40 Figure 4 is a perspective view of one of the blocks.

Referring to the drawings in detail, 10 and 11 indicate respectively the brake rods of the vehicle (not shown) while 12 indicates the truss rods. In vehicles of the above mentioned characters, these rods have a very long expanse, and this fact coupled with the very slender construction of these rods, allows said rods undue vibration, 45 especially when travelling over rough or irregular surfaces. As above stated, this vibration causes crystallization and resultant breakage. The device which is in the nature of a support for these rods, eliminates 50 this objection and can be conveniently arranged in position for use, or in other words

associated with said rods in the manner illustrated. The device includes an inverted substantially U-shaped section 13 of a frame, which has its intermediate portion 60 bulged as at 14 to accommodate itself to the drive shaft housing indicated at 15. The frame further includes a secondary section 16, which is bulged or otherwise suitably secured to the body portion of the section 13 65 as illustrated. The secondary section 16 is substantially co-extensive in length with the body portion of the main section, and has its intermediate portion bulged as at 17, this bulged portion being arranged directly opposite the bulged portion 14 of the main section, so that these bulged portions unitedly embrace the drive shaft housing above referred to. The parallel limbs 18 of the main section terminate to provide hook-like extremities 19 to receive the radius or truss rods 12, and arranged above these rods are bolts 20 which pass through the said parallel limbs and the hook-like extremities, thereby preventing undue vibration of said 75 rods.

Supported upon the main section of the frame adjacent each end thereof is a bearing block for the brake rods 10 and 11 respectively. Each bearing block includes a 80 lower section 21 and an upper section 22, the sections being bolted or otherwise suitably secured together by fastening elements 23 which also pass through openings 24 in both sections of the frame, so that the fastening elements 23 not only hold the sections of the block together, but also hold the block in its entirety fixed upon the frame.

The confronting faces of the block sections are provided with transverse grooves 25, these grooves unitedly defining bearings when the block sections are associated. The upper face of the lower block section is formed with a longitudinal groove 26 which 95 extends into the grooves 25 of said section, and positioned within said groove 26 is a strip of felt or the like 27. This felt is adapted to be saturated with oil through an opening 28 provided in the upper block section centrally thereof. The felt extends into the grooves 25 so as to lubricate the brake rods and to facilitate sliding of the latter in the bearing blocks. The device is very simple in 100 construction, and can be manufactured and 105 sold at a very nominal cost.

While it is believed that from the forego-

ing description, the nature and advantages of the invention will be readily apparent, I desire to have it understood that I do not limit myself to what is herein shown and described, and that such changes may be resorted to when desired as fall within the scope of what is claimed.

What I claim is:

1. A support for the brake and truss rods of a motor operated vehicle, comprising a pair of members secured together in face to face contact and adapted to be arranged transversely of the running gear of the vehicle, said members having their intermediate portions oppositely bulged to embrace the drive shaft housing on which the support is mounted, one of said members having its end portions depending therefrom in parallelism and terminating to provide U-shaped extremities adapted to receive the truss rods, bolts supported by the U-shaped extremities immediately above the truss rods and a two-part bearing supported on said member at each side of the bulged portion thereof, each of said bearings having transverse bores to receive the brake rods.
2. A support for the brake and truss rods

of a motor operated vehicle comprising a pair of members bolted together in face to face contact, the intermediate portions of said members being oppositely bulged to embrace the drive shaft housing of the vehicle on which the support is mounted, a bearing block supported on one of said members at each side of the bulged portion thereof, each block comprising superimposed sections having their confronting faces provided with a longitudinal groove and transverse grooves at both ends of the longitudinal groove, the corresponding transverse grooves of each section being arranged to receive the brake rods, said longitudinal grooves being adapted to receive a strip of felt saturated with lubricant, the ends of one of said members of the support being extended downwardly in parallel relation and terminating to provide U-shaped extremities arranged to receive the truss rods and bolts supported by the U-shaped extremities immediately above the truss rods for the purpose specified.

In testimony whereof I affix my signature.

ALBERT L. WOODSIDE.
